US00D618102S

(12) **United States Design Patent**
Toh et al.

(10) **Patent No.:** **US D618,102 S**
(45) **Date of Patent:** ** *Jun. 22, 2010

(54) **PORTION OF A CONTAINER**

(75) Inventors: **Kiat Cheong Toh**, Forest Hills, NY (US); **Liam Hawry**, Chicago, IL (US)

(73) Assignee: **Colgate-Palmolive Company**, New York, NY (US)

(**) Term: **14 Years**

(21) Appl. No.: **29/338,151**

(22) Filed: **Jun. 5, 2009**

D220,563 S 4/1971 Northgrave
D220,611 S 5/1971 Hills
D223,436 S 4/1972 Hills

FIG. 1 is a perspective view of the portion of a container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawing views are included for the purpose of showing environmental structure that forms no part of the claimed design.

1 Claim, 6 Drawing Sheets
